UNITED STATES PATENT OFFICE.

ALEXANDER WATKINS, OF LONDON, ENGLAND, ASSIGNOR TO THE SELF-ACTING SEWING MACHINE COMPANY, LIMITED, OF SAME PLACE.

SEWING-MACHINE.

SPECIFICATION forming part of Letters Patent No. 313,970, dated March 17, 1885.

Application filed April 23, 1884. (No model.) Patented in England November 19, 1877, No. 4,326.

To all whom it may concern:

Be it known that I, ALEXANDER WATKINS, a subject of Her Britannic Majesty, residing at London, England, have invented new and useful Improvements in Sewing-Machines, (for which I have obtained a patent in England, November 19, 1877, No. 4,326,) of which the following is a specification.

My invention has for its object the construction of sewing-machines in such a manner as to reduce friction in their working and to render the same more easily driven, so that they may be adapted to be run by a spring or other small motor.

15 Figure 1 is a front elevation, and Fig. 2 an end elevation, of the complete machine. Figs. 3 and 4 are back and end elevations of the same. Figs. 5, 6, and 7 represent the looper-shaft and its special bearings detached from the machine. Figs. 8 and 9 are details of improved apparatus for regulating the tension of the thread. Fig. 10 is an alternative detail of the presser-bar.

A A² are the table and standards or frame 25 of the machine. B is the main or driving shaft, to which manual or mechanical power is to be applied by means of a driving-pulley, U, thereon. C is a spur-wheel on this shaft, gearing with the wheel D, to which is connected the light rod E, which is jointed to the lever-bar F for working the needle. This lever-bar F has its fulcrum at G, which it will be seen is about midway between the two ends of the lever, thereby balancing the lever, or 30 nearly so, and diminishing the power required to work it. The requisite throw for working the needle H is obtained by connecting the rod E to the wheel D in the manner shown in Fig. 2, whereby the end of the rod has a suitable 35 crank motion imparted to it. By this arrangement it will be seen that the power required to work the needle from the driving-shaft is greatly diminished.

I is the looper-shaft, which is driven by the 45 wheel D, and is mounted so as to turn in hard steel bearings. This shaft is formed with a small journal at each end, as shown in Fig. 5, the journal at the end nearest the wheel D passing through a steel collar, K, inserted in 50 the bearing of the shaft, and the journal at the

other end working in a steel collar inserted in the bearing L. In each case the frictional surface in contact with the journal is only of the width of the collar in which the journal works.

Fig. 6 shows the steel collar K, and Fig. 7 the 55 steel collar in the bearing L. By forming and mounting the shaft in this manner a great diminution of bearing and frictional surface is secured, and wear of the parts is prevented by making them of steel or other suitable hard 60 material.

M is the presser-bar, the friction in the working of which is diminished by substituting for the ordinary spiral spring round a vertical spindle a flat spring, N, the end of which is 65 passed through an aperture in the bar, in which are formed slots to admit of the slight vertical movements of the bar on fixed studs, which, with the slots, serve as guides for the bar. Alternatively, I use a plate or shank (see Fig. 70 10) for the presser-bar with three slots, o o o, sliding on fixed studs, so as to ease the motion in lifting the foot and presser bar by providing additional points as guides for the sliding plate.

O is a vertical screw-rod with a button at 75 the top, by turning which the rod will be screwed down on a spring-brake, P, and cause the same to press on a small wheel, Q, on the shaft of the wheel D, and thereby stop or retard the motion of the machine, as may be required. On raising the rod O, by turning the screw in the reverse direction, the wheel Q will be released from pressure by the reaction of the spring fixed to the brake P.

R is the ordinary spool for supplying the 85 thread to the needle. The bottom flange of the spool R rests on a spring, S, and the tension of the thread is regulated, as required, by pressing the said flange onto the spring by means of a button, T, at the top of the bobbin. 90

For regulating the tension of the thread I may alternatively introduce the apparatus, Figs. 8 and 9. a and b are two plates mounted as shown, the upper plate, a, being formed, as shown in plan in Fig. 9, with a tongue projecting over and pressing upon the thread, the lower plate, b, being a simple disk. The requisite tension is applied to the thread by means of a screw and thumb-nut compressing the spiral spring C upon the upper plate. 100

Having now described my invention and the manner of its performance, be it known that what I claim as my invention, and desire to secure by Letters Patent, is—

5 1. The combination, in a sewing-machine, with the driving-shaft B, having gear-wheel C, of the shaft I, having reduced journals, hardened bearings for said journals, the gear-wheel D, having a crank-pin, the connecting-rod E, 10 the needle-operating lever F, pivoted near its center, and the needle-bar with which said lever is loosely connected, substantially as set forth.

2. In a sewing-machine, the combination, with the driving-shaft B, its gear-wheel C, the 15 looper-shaft I, having friction-wheel Q, and gear-wheel D, the latter provided with a crank-pin, the connecting-rod E, the needle-lever F, and the needle-bar, of the spring-brake P and the screw-rod O, by which the friction of said 20 brake is regulated, substantially as set forth.

London, this 7th day of March, A. D. 1884.

ALEXANDER WATKINS.
